(57) **CLAIM**

The ornamental design for a bracket, as shown and described.

DESCRIPTION

1.1 is a perspective view of a bracket showing my design;
1.2 is another perspective view thereof;
1.3 is a left side view thereof;
1.4 is another perspective view thereof;
1.5 is a front side view thereof;
1.6 is a bottom view thereof; and
1.7 is a top view thereof.
